His ATTORNEY

UNITED STATES PATENT OFFICE.

HERBERT B. TAYLOR, OF WESTFIELD, NEW JERSEY, ASSIGNOR TO HALL SWITCH & SIGNAL CO., A CORPORATION OF MAINE.

SEMAPHORE-BLADE GRIP.

1,266,346.

Specification of Letters Patent. Patented May 14, 1918.

Application filed August 17, 1916. Serial No. 115,559.

To all whom it may concern:

Be it known that I, HERBERT B. TAYLOR, a citizen of the United States, and a resident of the town of Westfield, county of Union, 5 and State of New Jersey, have invented certain new and useful Improvements in Semaphore-Blade Grips, of which the following is a specification.

My invention consists of certain new and 10 useful improvements in semaphore blade grips and more specifically in the novel means of attaching the semaphore blade grip to the semaphore mechanism shaft. This means has a number of advantages over the 15 old method of attachment, such as avoiding the destruction of the shaft bearings upon the removal of the semaphore blade grip from the shaft, on account of the pounding which was necessary to accomplish this in 20 the old form of semaphore blade grip.

The invention further eliminates the trouble heretofore experienced due to rusting of the semaphore blade grip to its shaft often necessitating the breaking of the same 25 to remove it from its shaft.

Another object of the invention is to enable a maintainer to loosen the blade grip and then to use both hands in the removal of the same. This is a vital feature as the blade 30 grip is of considerable weight. Defect of other blade grips in this respect has undoubtedly been the cause of many accidents.

A further advantage in this invention is in the fact that broaching of tapering holes 35 is absolutely eliminated and the blade grip will always be tight upon its shaft and will not be subject to breakage at this point, due to lost motion, as in the old type of blade grip.

40 Other novel features and advantages will be apparent from the accompanying description and will be more specifically described and claimed in the appended claims which form a part of this specification.

45 Referring to the figures on the accompanying drawing, Figure 1 is a front elevation of one form of the semaphore blade grip embodying my invention.

Fig. 2 is a partial section of the same 50 through A—A of Fig. 1.

Fig. 3 is a section through B—B of Fig. 1, with the bolt removed.

Fig. 4 is a front elevation of a semaphore 55 blade grip showing a modified form of my invention.

Fig. 5 is a section through C—C of Fig. 4.

Fig. 6 is a section through D—D of Fig. 4 with the bolt and spring removed.

Fig. 7 is a side elevation of a complete signal mechanism with my invention thereon. 60

Referring to the figures, I show a semaphore blade (1) attached by means of bolts (2) by a pressed steel spectacle carrying member (3). This is attached by means of bolts (4) to a main casting (5) which has a 65 flat upper face (6) in the center of which a 90 degree V shaped groove (7) is formed. A corresponding clamp casting (8) is arranged with a flat under-face (9) and a co-operating 90 degree V shaped groove (10) 70 arranged to act in co-operation with the V shaped groove (7) and the casting (5) to form a clamping jaw when these two castings are suitably clamped together. The casting (8) is provided with bolt holes (11) 75 arranged to align with the bolt holes (12) in the casting (5) and on the underside of bolt holes (12) in the casting (5) openings (21) are provided through the casting to permit of the insertion of nuts (13) in such 80 a manner that they cannot turn. The shaft (14) of the signal mechanism is provided with a square section (15) and a suitable head (16). It can be seen from the above description that if the bolts (17) are slackened 85 that the castings (8) and (5) may be separated sufficiently to allow the head (16) to slide in between the V shaped grooves (7) and (10). If these bolts (17) are now drawn up it will be seen that the whole device will be rigidly clamped to the square section (15) of the shaft (14), the head (16) 90 making it impossible for the device to slide off the end of the shaft.

In Fig. 4 I show a modified form of construction as follows:—There is a recess (18) formed in the upper casting (8) to take a spiral spring (19) about the shank of the bolt (17) and so arranged to press against the face (6) of casting (5) and the face (20) 95 of the recess (18).

The object of these springs (19) is to force the castings (5) and (8) apart when the bolts (17) are slackened and thereby facilitate the removal of the semaphore from 105 the shaft.

From the foregoing description, it will be seen that I have provided a very simple and convenient construction which will greatly facilitate the placing and removal 110

of semaphore blades in the field, which up to the present time has been a considerable source of trouble.

I do not wish to be restricted to the specific form as herein shown, as it is obvious that a considerable number of modifications can be made in the design of the apparatus without departing from the spirit of the invention.

10 Having described my invention what I claim as new and desire to secure by Letters Patent is:—

1. In combination with a railroad semaphore mechanism, a mechanism shaft, a 15 semaphore, and a semaphore blade grip comprising two parts adapted to be clamped together to retain the semaphore upon said mechanism shaft, clamping means and means incorporated in the blade grip for forcing said parts apart upon the slackening of said 20 clamping means.

2. In combination with a railroad semaphore mechanism, a semaphore, an operating shaft, a squared section formed between 25 two shoulders and adjacent the end of said shaft, and a semaphore blade grip comprising two parts adapted to be clamped together to retain the semaphore upon said shaft, clamping means and means incorporated in the blade grip for forcing said parts apart upon the slackening of said 30 clamping means.

3. In combination with a railroad semaphore mechanism, a semaphore, an operating shaft deformed adjacent the end thereof to prevent rotation thereon, and a 35 semaphore blade grip comprising two parts adapted to be clamped together to retain the semaphore upon said shaft, clamping means and means incorporated in the blade grip 40 for forcing said parts apart upon the slackening of said clamping means.

for forcing said parts apart upon the slackening of said clamping means.

4. In combination with a railroad semaphore mechanism, a semaphore, an operating shaft, a squared section formed between 45 two shoulders and adjacent the end of said shaft, a semaphore blade grip comprising two co-acting parts having V shaped grooves formed therein and adapted to fit upon the squared section between said shoulders, and bolts adapted to clamp the co-acting parts together to retain the semaphore upon said shaft, and means incorporated in the blade grip for forcing said parts apart upon the slackening of said clamping means. 50

5. In combination with a railroad semaphore mechanism, a semaphore, an operating shaft deformed adjacent the end thereof to prevent rotation thereon, a semaphore blade grip comprising two parts adapted to be clamped together to retain the semaphore upon the shaft, and means incorporated in the blade grip for forcing said parts apart upon the slackening of the clamping means. 55

6. In combination with a railroad semaphore mechanism, a semaphore, an operating shaft, a squared section formed between two shoulders and adjacent the end of said shaft, a semaphore blade grip comprising 60 two co-acting parts having V shaped grooves formed therein and adapted to fit upon the squared section between said shoulders, bolts adapted to clamp the co-acting parts together to retain the semaphore upon the shaft, and means comprising 65 springs for forcing said parts apart upon the slackening of said bolts. 70

In testimony whereof, I have signed my name to this specification.

H. B. TAYLOR.
